E. P. Penniman of Rochester N.Y.
Letters Patent No. 290 Dated June 18, 1850.

The Schedule referred to in these Letters Patent & making part of the same.

To all whom it may concern:

Be it known that I, Elijah P. Penniman, of the City of Rochester in the County of Monroe and State of New York have produced a new and Original Ornamental Design for Stoves, and I do hereby declare that the following is a full and exact description of the same.

My production consists in four Ornamental figures as shown in the accompanying drawings marked U.K. O.X.

What I claim as my production and desire to secure by Letters Patent is the combination of the four Ornamental figures (as represented) in the accompanying Drawings.

Witnesses.
